Patented Apr. 26, 1921.

FIG. 1.

FIG. 2.

FIG. 3.

Inventor

William E. Baker

Attorney
John M. Spellman

UNITED STATES PATENT OFFICE.

WILLIAM E. BAKER, OF WACO, TEXAS, ASSIGNOR TO WONDER TRAP CO., INC., OF WACO, TEXAS.

WIRE FABRIC.

1,375,810.

Specification of Letters Patent. Patented Apr. 26, 1921.

Application filed May 24, 1920. Serial No. 383,695.

To all whom it may concern:

Be it known that I, WILLIAM E. BAKER, a citizen of the United States, residing at Waco, in the county of McLennan and State 5 of Texas, have invented certain new and useful Improvements in Wire Fabrics, of which the following is a specification.

This invention relates to certain new and useful improvements in wire fabrics such 10 as are used in making baskets, animal cages and traps, stock nozzles and fences, etc.; and the primary object of the invention is to provide a fabric in which metal strips or 15 ribs and cross rods are united without the use of extraneous fastenings and with a minimum of bending so as to not weaken the parts by excessive bending.

The invention further aims to provide a 20 fabric which can be automatically produced by machinery and also economically produced with inexpensive equipment, and to provide a fabric in which holes or the like are entirely eliminated in the union of the parts.

25 The invention still further aims to simplify the joint connections between the strap-like ribs and the cross rods and to provide novel means for holding the rods against longitudinal movement.

30 Further and other objects will be later set forth and manifested in the course of the following description.

In the drawings:—

Figure 1 is a vertical sectional view of a 35 stock nozzle illustrating the present invention;

Fig. 2 is a detail view in side edge elevation showing the manner of connecting the parts;

40 Fig. 3 is a detail view in perspective of a section of the completed fabric; and

Fig. 4 is a section on line 4—4 of Fig. 3.

In proceeding in accordance with the 45 present invention metal ribs 1 of strip, strap, or ribbon form are employed and are passed through or between crimping or corrugating rolls which form the same with uniform corrugations or undulations having convex parts 2 and corresponding concave 50 parts 3. Wire rods 4 are placed in the concavities 3 on one side of the strips 1, and due to the parts 2 and 3 being alike on both sides of the strips, it will be apparent 55 that either side of the strips can be used equally well. Fig. 2 to its left shows the

rods as initially placed in the cavities 3, following which the straps 1 are subjected to the flattening out action of a roller or pressure device which mashes or flattens the corrugations as depicted to the right of 60 Fig. 2. Thus the rods 4 are frictionally gripped by the metal strips 1 which completely encircle the rods; and due to the nose 5 resulting from the double thickness formed by the doubling over of the parts 2, 65 the wire rods are securely and effectively held against movement.

For the dual purpose of increasing the effectiveness of the joint formed according 70 to the foregoing and for preventing slippage or movement of the rods transversely of the metal strips, the strips are crimped or given a concavo-convex formation as depicted at 6 in Fig. 4, this simultaneously imparting a corresponding contour to the 75 parts of the rods held in the sockets. Thus an increased frictional contact is provided between the parts and the strength of the joint is greatly augmented.

From the foregoing it will be apparent 80 that no slitting, or cutting of holes or openings in the metal strips, is required and that frictional contact alone is relied upon in order to connect the parts. Further the wire rods are bent but slightly as shown in 85 Fig. 4 and the metal strips are bent to a minimum, the bending moreover involving a double thickness provided as to one-half of the socket formed for the reception of the wire.

90 Further the bowing or the concavo-convex formation of Fig. 4 results in greater strength being imparted to the metal strips, reinforcing the same in an obvious manner.

Owing to the width of the strips it will 95 be apparent that they afford a relatively wide gripping area for the wires, and in addition the bending of the strips does not appreciably weaken them.

What is claimed is:

1. In a wire fabric, transversely corrugated metal strips, and wire rods disposed in the concavities on one side of the strips, and the corrugations being flattened to completely encircle and tightly grip the rods, 105 said strips and rods being formed with bowed parts extending transversely of the strips to hold the rods against movement transversely of the strips.

2. A wire fabric composed of metal strips 110

and wire rods disposed on one side of the strips, said strips having bowed parts between the wire rods, which parts are folded over to completely encircle and tightly grip 5 the rods and to form a double layer of metal to overlie the rods.

3. A wire fabric composed of metal strips and wire rods disposed on one side of the strips, said strips having bowed parts between the wire rods, which parts are flat- 10

tened over to completely encircle and tightly grip the rods, and also to form a double layer of metal which overlies the rods, said strips and rods being formed with bowed parts extending transversely of the strips 15 to hold the rods against movement transversely of the strips.

In testimony whereof I have signed my name to this specification.

WILLIAM E. BAKER.
